UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

DUST-GUARD.

No. 802,530.

Specification of Letters Patent.

Patented Oct. 24, 1905.

Application filed August 29, 1904. Serial No. 222,530.

To all whom it may concern:

Be it known that I, JOHN W. STEPHENSON, of Toledo, Lucas county, Ohio, have invented 5 a new and useful Dust-Guard, of which the following is a full, clear, and exact description, reference being had to the accompanying drawings, forming part of this specification, in which—

Figure 1 is a rear elevation of a journal-box 10 constructed in accordance with my invention, the car-axle being shown in vertical cross-section. Fig. 2 is a plan view, partly in horizontal section, on the line II II of Fig. 1. Fig. 3 is a vertical section on the line III III 15 of Fig. 1. Fig. 4 is a detail view showing the packing-ring, and Fig. 5 is a perspective view of the lock by which the cover-plate and dust-ring are retained.

My invention is designed to provide means 20 for effectually excluding dust from entering the rear end of a car-axle box. The problem of thus excluding the dust is a difficult one, because the contracted space at the back of such box makes it difficult to apply efficient 25 devices for the purpose.

My invention accomplishes the result by very simple means which do not add substantially to the weight of the parts and which are not clumsy and can be removed and ad- 30 justed quickly.

In the drawings, 2 is the car-axle journal. 3 is the box, and 4 is the car-wheel hub. At the rear of the box, in a recess 5 thereon, is a ring 6 of L shape in cross-section. This ring 35 has an opening of greater diameter than the diameter of the axle, so as to fit loosely thereon, and it also has freedom of movement in the recess 5. The ring 6 carries a packing-ring 7, which is sectional and is seated in the ring 40 6 and is held therein by a flat cover-ring 8, which fits against the ring 6 and against the rear face of the axle-box. The cover-ring 8 is provided at its upper portion with supporting projections 9, which rest upon the ring 6 and support the cover-ring, and the cover- 45 ring may be held in place by locking devices 10, similar to those shown in my Patent No. 742,750, which are held to the axle-box by bolts 11, fitted with springs 12 and cotters 13, 50 or the cover-ring may be otherwise held. It moves with the axle and with the ring 6 in the vertical motion of the axle and slides freely against the rear face of the box and back of the locks 10. The locks 10, unlike

the locks of my said patent, do not slide with 55 the axle; but the rings 6 and 8 slide independently of the locks. The locks 10 have projections 10', which fit in small recesses on the face of the journal-box, as shown in Figs. 3 and 5. 60

The use of the dust-guard ring 6 and the retaining-ring 8 makes the device extremely simple in construction and very light and enables it to be removed and adjusted quickly.

The parts may be modified in various ways 65 within the scope of my invention, since

What I claim is—

1. In combination with a journal-box, a dust-guard comprising a packing-carrying ring placed loosely around the axle, and a separate 70 sliding cover-ring over said packing-ring; substantially as described.

2. In combination with a journal-box, a dust-guard comprising a ring placed loosely around the axle-opening and adapted to carry packing material, and a sliding cover-ring over the said ring and bearing against the rear outer face of the journal-box; substantially 75 as described.

3. In combination with a journal-box, a dust-guard comprising a ring placed loosely around the axle-opening in a recess in the rear face of the journal-box, and a sliding cover-ring fitting against the rear outer face of the journal-box over the said ring; substantially 80 as described.

4. In combination with a journal-box, a dust-guard comprising a packing-carrying ring placed loosely around the axle-opening, and a cover-ring fitting against the rear outer face 90 of the journal-box over the said ring and supported thereby; substantially as described.

5. In combination with a journal-box, a dust-guard comprising a packing-carrying ring placed loosely around the axle-opening, and a cover-ring fitting over the said ring and supported thereby, said cover-ring having a sliding bearing against the rear outer face of the journal-box; substantially as described. 95

6. In combination with a journal-box, a dust-guard comprising an open-sided ring of angular cross-section for carrying packing material, and a sliding cover-ring fitting over the said ring and bearing against the rear outer face of the box; substantially as described. 100

7. In combination with a journal-box, a dust-guard comprising a ring placed around the axle-opening and adapted to carry packing

material, and a separate sliding cover-ring fitting over the said ring, and over the packing material; substantially as described.

8. In combination with a journal-box, a dust-guard comprising a ring of angular cross-section for carrying packing material, and a cover-ring fitting over said ring and over the packing material and bearing on the rear outer face of the journal-box; substantially as described.

9. A journal-box having a packing-carrying

ring, a sliding cover-ring, and a lock for the cover-ring, said cover-ring bearing against the rear outer face of the box and sliding with the packing-carrying ring independently of the lock; substantially as described.

In testimony whereof I have hereunto set my hand.

JOHN W. STEPHENSON.
